UNITED STATES PATENT OFFICE.

THEODORE E. FRIEND, OF NORWALK, OHIO.

CARBURETER.

1,180,389.

Specification of Letters Patent. Patented Apr. 25, 1916.

Application filed October 16, 1914. Serial No. 866,990.

To all whom it may concern:

Be it known that I, THEODORE E. FRIEND, a citizen of the United States, and a resident of Norwalk, in the county of Huron and 5 State of Ohio, have made certain new and useful Improvements in Carbureters, of which the following is a specification.

My invention relates to improvements in carbureters, and it consists in the constructions, combinations and arrangements herein described and claimed.

An object of my invention is to provide a device in which the regulation is practically maintained by the velocity of the air 15 flow as a separate factor.

A further object of my invention is to provide an effective means for balancing the fluid head pressure against a regulating valve such that the first said object can be 20 accomplished.

A further object of my invention is to provide a form of air passage and a form of regulating valve such that the aforesaid objects can be accomplished with as little friction 25 as possible.

A further object of my invention is to dispose the fuel jet in reference to the aforesaid form of air passage such that a thorough mixing of the air and fuel is accomplished.

A further object of my invention is to provide means for regulating the primary opening or aperture thereby allowing of closer 30 adjustments.

The following specification and the appended claims make clear my invention in detail.

My invention is illustrated in the accompanying drawings which form a part of this 40 application in which—

Figure 1 is a vertical section through the device, Fig. 2 is a plan view of the float chamber with the integral air passage and the float in place, Fig. 3 is a plan view of the 45 cover removed, Fig. 4 is a front view of the float chamber with the integral air passage, Fig. 5 is a front view of the air valve housing with the segment of a cylinder integral and the air valve and oscillating plate in 50 place, and Fig. 6 is a plan view of the air valve with the attached oscillating plate.

In carrying out my invention I provide a main casing 1, the interior of which constitutes a float chamber 2. The casing 1 is pro-

vided with an extension 3, which forms a 55 valve chamber 4. A float valve needle 5 is arranged within the valve chamber 4 to close the fuel inlet 6. The float valve needle 5 is carried by the outward end of the float lever 7 by means of the ball joint 8. 60 The float lever 7 is hinged on a pivot 9 carried by the walls of the extension 3. The float 10 is carried by the inward end of the float lever 7 by means of the screw 11. A removable cap 12 is provided for the valve 65 chamber 4 to allow inspection and assembling.

Integral with the main casing 1 are the walls 13 forming the portion of the air passage 14 which is curved and of triangular 70 cross-section. The lower portion of the walls 13 terminate in the flange 15, while the upper portions terminate free and central within the upper portion of the main casing 1. 75

A cover 16 is arranged to rest upon the open end of the main casing 1, and upon the free ends of the walls 13. An extension 17 is provided on the cover 16, that conforms with and fits around the free ends of the 80 walls 13, thus providing a depression into which the gasket 18 is placed to provide a gas tight joint. The cross-section of the air passage 14 is arranged such that two of the walls 13 form the convex side of the air 85 passage 14, while the third of the walls 13 forms the concave side of the air passage 14. Central of the bend and on the convex side of the air passage 14 within the walls 13 is disposed the fuel jet 19, driven or screwed 90 into a boss 20. In the concavity of the bend of the air passage 14 and integral with the walls 13 is formed the boss 21, and coincidentally on the periphery of the cover 16 is a second boss 22. A fuel adjusting needle 95 52 is fitted into the bosses 21 and 22, screwing into the former and extending through the air passage 14, enters the fuel inlet 23 on a taper.

On the top face of the cover 16 is formed 100 a flange 24, and upon this flange rests the outlet tube 25 by means of a similar flange 24'. The passage way 26 of the outlet tube 25 is of triangular cross-section at the bottom and merges into a circular cross-section 105 at the outlet. A butter-fly throttle valve 27 is disposed in the outlet of the outlet tube 25. A short passage way 28 is provided centrally

through the cover 16. The cross-sections of the passages 14, 26 and 28 coincide to form a continuous passage-way. The outlet tube 25 and the cover 16 are held to the main casing 1 by means of screws passing through the flanges 24 and 24' and screwed into the bosses 29 provided coincidentally on the main casing 1 within the float chamber 2.

On line with the fuel jet 19, within the 10 main casing 1, is provided a boss with a threaded aperture into which the filler plug 30 is screwed, for the purposes of providing means for introducing the fuel jet 19.

Upon the flange 15 rests a valve casing 31 15 provided with a similar flange 15'. Screw holes 32 are tapped into the flange 15 and screws are provided to clamp the two flanges 15 and 15' together. The general cross-section of the valve casing passage way 33 is 20 triangular and coincides with that of the passage 14 to form a continuous passage. A flange 33 is provided on the inlet end of the valve casing 31, upon which rests an inlet tube 34 provided with a similar flange 33'. 25 The passage-way 35 of the inlet tube 34 is of triangular cross-section at the inward end and coincides with that of the passage-way 32, while the outer portion merges into a circular cross-section. On the dividing line between the inlet tube 34 and the valve casing 31 in the upper portion of the passages 32 and 35 is disposed a pivot 36 extending into bearings provided in the flanges 33 and 33'. Around the pivot 36 and continuous with the 30 passage-way 32 is formed a quarter segment of a cylinder 37 within extending walls 38 of the valve casing 31. An extension 33'' of the flange 33' is provided to cover the outer portion of the segment of a cylinder 37. A 35 portion of the inlet tube 34 is extended at 39 around the pivot 36 to provide the opening 40 around the upper portion of the pivot 36 into the segment of cylinder 37.

A flat swinging valve 41 of triangular 45 cross-section is fastened upon the pivot 36 on a base side and extends at an angle into the passage-way 32. An oscillating plate 42 is fastened on one side to the pivot 36, and is made to rotate within the segment of cylinder 37 with a close fit. A boss 43 is formed upon the extension 38, and an adjusting screw 44 is screwed through the boss 43 into the segment of cylinder 37. A lock nut 45 provides means for maintaining the adjustment of the screw 44. Engaged between the inward end of the screw 44 and the oscillating plate 42 is the compensating spring 46. A boss 47 maintains the position of the spring 46 upon the oscillating plate 42.

60 Upon the bottom of the valve casing 31 is a boss 48 through which an adjusting screw 49 is screwed. A lock nut 50 provides means for maintaining the adjustment of the screw 49. The inward end of the screw 49 engages against the lower face of the valve

41 and maintains a certain open position of the valve 41 in reference to the angular walls 51.

As the fuel enters into the float chamber the float rises until the valve needle 5 closes the fuel inlet 6. The suction of the engine will cause fuel to be drawn through the fuel jet 19 and sprayed into the air passage through the fuel inlet 23 when the needle valve 52 is open. The needle valve 52 provides a means of spreading the spray such that it may be used more efficiently. The float maintains a nearly constant level of fuel within the float chamber in reference to the fuel inlet 23.

70 It will be noticed that the fuel inlet 23 being in the apex of a cross-section of the passage 14 has a tendency to provide a spray that fills the cross-section of the passage such that very little air can slip by without 75 being carbureted.

80 In the operation of the air valve 41, the oscillating plate 42 within the segment of cylinder 37 provides a means for maintaining a balance against the fluid head pressure 90 upon the valve 41, thus allowing the air velocity to mainly operate the valve. The advantage of this is great for the air velocity varies at a ratio with the engine speed and is uninfluenced by the throttle positions, 95 therefore more constant mixtures are generated irrespective to the throttle positions, and greater accelerations are possible at any speed or load.

100 It will be observed that the area of the oscillating plate 42 is shown as being of less area than that of the valve 41. Also that the mean effective turning moments are of different magnitude, for these members are of different shape. Whereas it is desired to have a practically perfect balance maintained against the fluid head pressure upon the valve 41, by means of the oscillating plate 42, it can be proven, experimentally, that when this balance is obtained the area 110 of the valve 41 is greater than the area of the plate 42. This difference of area is accounted for by the fact that the atmospheric pressure upon the member 42 is static, while upon the valve 41 it is not. In 115 other words, the flow of the air into the passageway has the tendency to lessen the atmospheric pressure upon the valve 41.

120 It will be noticed that the air has a very free ingress into the air passage by the valve 41 as there are no sharp corners to turn. This is an advantage in helping to make the carburetor efficient.

125 Another feature of my invention is the means provided for adjusting the primary opening. This is accomplished by using a swinging triangular valve disposed at an angle within a passage of triangular cross-section whereby a valve action is maintained between the free angular edges of the valve 130

and the adjacent angular sides of the passage, and using an adjusting screw for normally keeping the valve a portion of the way open.

5 The object in using a swinging air valve in combination with the oscillating plate and a segment of a radial cylinder instead of using a circular air valve in combination with a circular piston and cylinder for the 10 same purpose is that the swinging air valve can be made to operate with less friction, and the effect of the velocity, which is of small magnitude, is magnified upon a swinging valve disposed at an angle.

15 Although I indorse the construction as herein described, I do not limit myself to that construction only, for there are numerous other combinations for accomplishing the same purpose.

20 I claim:—

1. A carbureter comprising an air passage, a fuel inlet disposed within said air passage, an inwardly opening, automatic, air regulating valve mounted to operate in conjunction with and normally close the inlet end of said air passage except for a primary inlet adjacent to said valve into said air passage, a chamber off-set to and contiguous with said air passage and adjacent 25 to said valve, an extension of said valve arranged to operate with a close and constant fit within said chamber and conjunctly with said valve, such that a constant counter-action is maintained against the effect of 30 the suction pressure upon said valve, and said valve arranged to receive the impact of the air flow into said air passage.

2. A carbureter comprising an air passage of triangular cross-section, a fuel inlet 40 disposed within said air passage, means for providing a constant head pressure of fuel to said fuel inlet, a pivot arranged on a side of the inlet end of said air passage, a swinging, inwardly opening, automatic, air

45 regulating valve of triangular cross-section arranged on a side on said pivot such that a valve action is provided between the free angular sides, thereof, and the adjacent angular walls of said air passage, a primary

50 inlet adjacent to said valve into said air passage, means for providing a resilient reaction upon said valve, a chamber contiguous with said air passage radially around said pivot, and an extension of said valve 55 arranged to oscillate with a close fit within said chamber and conjunctly with said valve, for the purpose of providing a counter-action against the suction pressure upon said valve.

60 3. A carbureter comprising an air passage of triangular cross-section, a fuel inlet disposed within said air passage, a float chamber operating conjunctly with said fuel inlet, a pivot arranged on a side of the inlet 65 end of said air passage, a swinging, in-

wardly opening, automatic, air regulating valve of triangular cross-section arranged on a side on said pivot, such that a valve action is provided between the free angular sides, thereof, and the adjacent angular 70 walls of said air passage, means for adjusting said valve partially open to provide a primary inlet adjacent to said valve into said air passage, means for providing a resilient reaction upon said valve, a segment 75 of a cylinder contiguous with said air passage radially around said pivot, and a plate arranged on a side on said pivot to oscillate within said segment of cylinder with a close fit and conjunctly with said valve, for the 80 purpose of providing a counter-action against the suction pressure upon said valve.

4. A carbureter comprising an air passage of triangular cross-section, the central portion being curved such that one of the 85 sides forms the concavity of said bend and the oppositely adjacent sides form the convexity of said bend, the free ends of said air passage forming the inlet and outlet, respectively, to said air passage, a fuel inlet 90 disposed on the convex side of said air passage, a pivot arranged in the inlet end of said air passage on the side contiguous to said concave portion of said air passage, a swinging, inwardly opening, automatic, air regulating valve of triangular shape arranged on a side on said pivot, extending across said air passage inwardly at an angle, and performing a valve action between the free angular sides, thereof, and the adjacent angular 95 walls of said air passage, a segment of a cylinder contiguous with said air passage radially around said pivot, a plate arranged on a side on said pivot to oscillate within said segment of cylinder with a close fit and 100 conjunctly with said valve, for the purpose set forth, means for providing a resilient reaction upon said valve, and a primary inlet adjacent to said valve into said air passage.

5. A carbureter comprising an air passage of triangular cross-section, a fuel inlet disposed within said air passage, a pivot arranged on a side of the inlet end of said air passage, a swinging, inwardly opening, 110 automatic, air regulating valve of triangular shape arranged on a side on said pivot such that a valve action is provided between the free angular sides of said valve and the adjacent angular walls of said air passage, 115 a primary inlet adjacent to said valve into said air passage, and means for providing a resilient reaction upon said valve.

6. A carbureter comprising an air passage of triangular cross-section, a fuel inlet 120 disposed in the apex of a cross-section of said air passage, and means for spreading the discharge from said fuel inlet outwardly toward the angular walls of said air passage confining said fuel inlet.

7. A carbureter comprising a curved air passage of triangular cross-section with two of the angular walls forming the convex side of said air passage, and the third wall forming the concave side of said air passage, a fuel inlet on the convex side of said air passage in the apex of a cross-section, thereof, and means for spreading the dis-

charge from said fuel inlet outwardly toward the angular walls of said air passage confining said fuel inlet. 10
